Garrison Smith & Henry Brown, of Philadelphia, Pa.
Assignors to Hayward, Bartlett & Co., of Baltimore, Md.
Letters Patent No. 1153. Dated Oct. 4, 1859.

The schedule referred to in these Letters Patent and making part of the same.

To all whom it may concern:

Be it known, that Mr. Garrison Smith & Henry Brown, of the City and County of Philadelphia, and State of Pennsylvania, have produced a new and original design for a Cook Stove, Designated "The Patapsco Cook," & we do hereby declare that the following is a full, clear, and exact description of the same; reference being had to the annexed drawing forming part of this Specification.

The side plate A, bears two panels B. and C. raised by mouldings a' and b'. Above the panels it is ornamented in bas-relief by fruit c. and foliage t. The panel B. is ornamented with a figure made up of a central globular projection d. from which radiates foliage and fruit e: f. g: the design and configuration being as shown in the drawing. The panel C. bears a similar ornament D.

The front plate E, is of swell form and has four doors F and G. the upper ornamented as shown at h. and the latter each embellished with an ornament in bas-relief made up of globular projection i. figure j. and radial foliage k. m. The design and configuration of these several ornaments being as shown in the drawing.

The back plate P. is of swell form and bears in bas-relief central globular figure n. with covering o. through which passes branches p. of foliage q. r. s. and fruit t; the design configuration and arrangement being as shown in the drawing.

The foot is ornamented with sweeping foliage a, arranged and configured as shown in the drawing.

We claim the design, configuration and arrangement of the several ornaments in bas-relief as herein described and set forth in the drawing as the design for Stove "Patapsco. Cook."

In testimony whereof we have hereunto signed our names before two subscribing Witnesses.
